UNITED STATES PATENT OFFICE

109,932

DESIGN FOR AN ELECTRIC OPERATED PUMP UNIT

Vaughan L. Andrew, Superior, Wis.

Application August 16, 1937, Serial No. 71,102

Term of patent 7 years

To all whom it may concern:

Be it known that I, Vaughan L. Andrew, a citizen of the United States and a resident of Superior, in the county of Douglas, and State of Wisconsin, have invented a new, original, and ornamental Design for an Electric operated pump unit, of which the following is a specification, reference being had to the accompanying drawing, forming part thereof.

Figure 1 is an end elevation of an electric operated pump unit, showing my new design.

Figure 2 is a side elevation of the same.

I claim:

The ornamental design for an electric operated pump unit, as shown.

VAUGHAN L. ANDREW.
